(57) **CLAIM**

The ornamental design for a solarium apparatus, as shown and described.

DESCRIPTION

FIG. 1 is a top plan view of a solarium apparatus, showing the design;

FIG. 2 is a bottom plan view thereof;

FIG. 3 is a front elevational view thereof;

FIG. 4 is rear elevational view thereof;

FIG. 5 is a right side view thereof;

FIG. 6 is a left side view thereof; and,

FIG. 7 is a perspective view thereof.

The dashed lines are included for the purpose of showing environmental structure and form no part of the claimed design.

1 Claim, 7 Drawing Sheets
